Primary Examiner — Richard Edgar*Assistant Examiner* — Alexander J David(74) *Attorney, Agent, or Firm* — Andrew F. Young, Esq.;
NOLTE LACKENBACH SIEGEL(57) **CLAIM**

The ornamental design for a robot, as shown and described.

DESCRIPTION

FIG. 1 is a top perspective view of a robot, showing my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The dash-dot-dash lines mark the boundary of claimed portions beyond which no claim is made. The dash-dash lines represent unclaimed environmental matter and form no part of the claimed design.

1 Claim, 7 Drawing Sheets(56)
